UNITED STATES PATENT OFFICE.

ANDREW EPPLER, OF LYNN, MASSACHUSETTS, ASSIGNOR TO UNITED SHOE MACHINERY COMPANY, OF PATERSON, NEW JERSEY, A CORPORATION OF NEW JERSEY.

ROUNDING AND CHANNELING MACHINE.

1,080,902.

Specification of Letters Patent.

Patented Dec. 9, 1913.

Application filed July 1, 1911. Serial No. 636,493.

To all whom it may concern:

Be it known that I, ANDREW EPPLER, a citizen of the United States, residing at Lynn, in the county of Essex and State of Massachusetts, have invented certain new and useful Improvements in Rounding and Channeling Machines; and I do hereby declare the following to be a full, clear, and exact description of the invention, such as will enable others skilled in the art to which it appertains to make and use the same.

The present invention relates to rounding and channeling machines which are employed to operate upon shoe soles after they have been incorporated in boots and shoes.

The invention is intended more especially as an improvement on the Goodyear rough rounding and channeling machine shown and described in the patent to French and Myer, 599,602, February 22, 1898, although it is not confined in its application to this machine but may be embodied with advantage in other forms of rounding and channeling machines. Machines of this class are employed for rounding the edge of the sole and cutting a channel in the surface of the same after the sole has been incorporated in the shoe and preparatory to the sewing operation. In addition to the above described operations, it is oftentimes essential to perform still further operations upon the sole, such, for example, as beveling the margin of the sole at the shank in order to form a light edge shank, which operations have heretofore been performed separately from the rounding and channeling operations.

The object of the present invention is to enable such a further operation to be performed conjointly with the rounding and channeling operations and without interfering with the speed or accuracy of these latter operations.

With this end in view a feature of the invention consists in the combination in a machine of the character described of an auxiliary knife for skiving the margin of the sole and rounding and channeling knives for trimming the edge and cutting a channel in the surface of the sole, respectively.

A further feature of the invention contemplates the provision in a rounding and channeling machine of an auxiliary knife arranged to operate upon the sole, and which may be thrown into and out of operation

during the continuous operation of the rounding and channeling knives.

Still further features of the invention comprise certain novel features of construction, combinations and arrangements of parts hereinafter described and claimed, the advantages of which will be apparent to those skilled in the art from the following description.

In the accompanying drawings illustrating the preferred form of the invention, Figure 1 is a view showing a detail of the side elevation of a rounding and channeling machine embodying the several features of the invention in their preferred form and illustrating the auxiliary knife in an inoperative position; Fig. 2 is a view similar to Fig. 1 and illustrating the auxiliary knife in operative position; Fig. 3 is a view showing a detail of the front elevation of the rounding and channeling machine; Fig. 4 is a longitudinal section taken upon the line 4—4 of Fig. 3; Fig. 5 is a detail illustrating an elevation of the sole supporting spindle and channeling knife mounted thereon; Fig. 6 is a detail sectional view taken on the line 6—6 of Fig. 4; and Fig. 7 is a plan view of the supporting plate for the sole support illustrating the mechanism for clamping the channeling knife in position.

In the machine shown in the drawings, 1 indicates the trimming knife, 2 the work support or crease guide, 3 the feed plate, 4 the forepart gage, 5 the channeling knife, and 6 the vertically movable sole support on which the channeling knife is mounted. In order to cut the channel nearer to the edge of the sole along the fore part than at the shank, the forepart guide 4 is mounted upon the end of a supporting arm 7 which is pivoted at 8 to the machine frame and is provided with a depending bracket 9 adjustable in and out on the arm 7 and which carries a shoe 10 upon its lower end. The channeling knife 5 and sole support 6 are mounted upon a vertically sliding frame 11 which is provided with a rack 12 formed upon one face. An oscillatory toothed segment 13 engages with the rack and is operated by a curved lever 14 having an arm 15 which engages with the shoe 10 so that upon a downward movement of the arm 7 a slight upward movement in a vertical direction is imparted to the sole support and channel-

ing knife. The sole support 6, as indicated clearly in Figs. 4 to 7 inclusive, consists of an anti-friction roll journaled on a vertical spindle 18 which is supported upon the sliding frame 11. The channeling knife 5 is adjustably clamped upon the sole supporting spindle 18 by a clamp block 20 and clamping screw 21. The anti-friction roll is retained in position upon the spindle by a latch arm 22 which may be readily swung out of the way in order to remove the roll and adjust the channeling knife. All of the above described parts have the same construction and mode of operation as the corresponding parts in the Goodyear machine above referred to and are only briefly described herein in consequence thereof.

In the illustrated embodiment of the invention, a skiving knife is provided which follows the rough rounding and channeling knives in their operations upon the sole and which may be thrown into and out of operation at the will of the operator during the continuous operation of these knives. This skiving knife is employed for beveling or skiving the margin of the outsole at the shank in order to form what is termed a light edge shank, thus imparting a better finish to the shoe and enabling this portion 30 of the sole to be more readily operated upon in the subsequent leveling operation.

In the simplest and most efficient form of the invention which has yet been devised, the beveling knife is normally arranged in operative relation to the sole and is automatically moved into an inoperative position upon the downward movement of the forepart guide into engagement with the shoe. Thus the movement of the beveling 40 knife into and out of operative position is effected at the proper time without necessitating a slowing down of the machine or in any way hindering or changing the action of the rounding and channeling knives. In 45 the construction illustrated, the auxiliary or shank beveling knife, as it may be termed, is indicated at 25 in close proximity to the channeling knife 5 and arranged to follow the channeling and rounding knives in their 50 action upon the sole. The knife 25 is adjustably supported upon the upper end of a curved arm 26 in order that it may be moved toward and from the channeling knife as desired. The arm 26 is pivoted at 55 28 to the lower end of the sliding frame 11 in order that the auxiliary knife 25 and the channeling knife 5 shall have the same vertical movement, thus insuring that the beveled surface shall extend from the edge of 60 the sole to approximately the base of the channel flap, as shown clearly in Fig. 2 of the drawing. The knife 25 is normally retained in operative engagement with the work by a compression spring 30 which is 65 interposed between the rear face of the arm

26 and the frame of the machine. In order to automatically move the knife out of engagement with the work upon the downward movement of the forepart guide into operative position, a dog 31 is mounted upon the lever 14 and is arranged to engage with a stud 32 projecting from the arm 26. Thus upon an oscillatory movement of the curved lever 14 due to the downward movement of the arm 7, the dog 31 engages with the stud 32 and rocks the arm 26 against the action of the spring 30 to remove the knife 25 from engagement with the work. In order to regulate the depth of the cut of the knife 25, an adjusting screw 33 is threadedly mounted in the lower portion of the arm 26 and has its free end engaging with one face of the frame 11. The adjusting screw 33 is locked in any adjusted position by a locking nut 34.

While it is preferred to employ the specific construction and arrangement of parts shown and described, it will be understood that this construction and arrangement is not essential except so far as specified in the 90 claims and may be varied or modified without departing from the broader features of the invention.

Having thus described one form of the invention, what is claimed is:—

1. A rounding and channeling machine having, in combination, a crease guide, a trimming knife and a channeling knife for respectively rounding the edge of the sole and cutting a channel in the surface of the same, and an auxiliary knife arranged to be moved into and out of an operative position during the continuous operation of the trimming and channeling knives.

2. A rounding and channeling machine comprising a crease guide, a trimming knife for rounding the edge of the sole and an auxiliary knife for beveling the margins of the sole arranged to be moved into and out of an operative position during the continuous operation of the trimming knife.

3. A rounding and channeling machine having, in combination, a trimming knife and a channeling knife for respectively rounding the edge of the sole and cutting a channel in the surface of the same, a crease guide, a forepart guide, an auxiliary knife, and connections between the auxiliary knife and forepart guide for moving the knife into an inoperative position upon a movement of the forepart guide into engagement with the shoe.

4. A rounding and channeling machine comprising a channeling knife for cutting a channel in the surface of the sole, a forepart guide, connections between the forepart guide and channeling knife for moving the channeling knife vertically upon a downward movement of the forepart guide, an auxiliary knife arranged to move ver-

- tically with the channeling knife, and means for moving the auxiliary knife into and out of operation during the continuous operation of the channeling knife.
- 5 5. A rounding and channeling machine having, in combination, trimming and channeling knives, a crease guide, a forepart guide, an auxiliary knife, a pivoted arm supporting the auxiliary knife, means normally tending to retain the auxiliary knife in operative position, and connections between the arm and forepart guide arranged to move the knife out of operative position upon the downward movement of the forepart guide.
- 10 6. A rounding and channeling machine comprising a trimming knife, a forepart guide, an auxiliary knife, a pivoted arm supporting the auxiliary knife, a curved lever operatively connected with the forepart guide, and connections between the lever and arm arranged to rock the arm and move the knife into an inoperative position upon the downward movement of the forepart guide.
- 15 7. A rounding and channeling machine comprising a trimming knife for rounding the edges of the sole, a crease guide, an auxiliary knife for beveling the margin of the sole, means normally tending to move
- the auxiliary knife into an operative position, and a stop for limiting the inward movement of the auxiliary knife.
8. A rounding and channeling machine, having, in combination, a crease guide, a trimming knife and a channeling knife for respectively rounding the edge of the sole and cutting a channel in the surface of the same, and an auxiliary knife for skiving the margin of the sole to form a thin edge.
- 35 9. A rounding and channeling machine, having, in combination, a crease guide, a trimming knife and a channeling knife for respectively rounding the edge of the sole and cutting a channel in the surface of the same, and a skiving knife arranged to bevel the margin of the sole beneath the channel flap to form a thin edge.
- 40 10. A rounding and channeling machine comprising a crease guide, a trimming knife for rounding the edge of the sole, a skiving knife for beveling the margin of the sole at the shank, and means for moving the skiving knife into an inoperative position when the trimming knife is operating about the ball portion of the sole.
